FINGER-TIP SAFETY EJECTOR FOR GUNS

John T. Hansen, Suring, Wis.

Application October 22, 1947, Serial No. 781,401

10 Claims. (Cl. 42—6)

1
This invention comprises novel and useful improvements in a fingertip safety ejector for guns, and more specifically pertains to an attachment to facilitate the insertion of or removal of shells from the breech of guns.

The principal object of this invention resides in providing an improved means to facilitate the insertion of shells in the magazine of a gun or the removal of shells therefrom.

An important feature of the invention resides in providing a simple attachment construction which may be readily applied to existing types of guns whereby shells may be inserted or removed from magazines in an improved manner with a minimum of difficulty.

An important object of the invention is to provide an attachment in accordance with the foregoing objects and features which shall be of simple construction, economical to manufacture, highly efficient in use and dependable and sure in its operation.

These, together with various ancillary objects of the invention which will later become apparent as the following description proceeds, are attained by this device, a preferred embodiment of which has been illustrated by way of example only in the accompanying drawings, wherein:

Figure 1 is a top plan view of a portion of the breech mechanism of a gun showing the device applied thereto;

Figure 2 is a side elevational view of the construction of Figure 2;

Figure 3 is a horizontal sectional view through the mechanism of Figure 2, taken substantially upon the plane of the section line 3—3 thereof and showing the construction in its idle or non-operative position;

Figure 4 is a perspective view of the fastening means of the attachment;

Figure 5 is a perspective view of a portion of the attachment;

Figure 6 is a perspective view of an ejector opening closure of the breech mechanism of a gun showing a part of the invention applied thereto;

Figure 7 is a transverse vertical sectional view taken substantially upon the plane of the section line 7—7 of Figure 9;

Figure 8 is a vertical longitudinal sectional view taken substantially upon the plane of the section line 8—8 of Figure 7; and

Figure 9 is a view similar to Figure 3 but showing the parts in position for inserting or removing a shell from the magazine of a gun.

Referring now more specifically to the accompanying drawings wherein like numerals designate similar parts throughout the various views, the numeral 10 designates a portion of the casing of the breech of a gun, having the customary barrel 12 associated therewith, and having cheek

plates 14 for the reception of the stock of a gun, not shown.

This casing 10 is provided with the customary ejector and filling aperture or opening 16, which, in accordance with conventional types of guns and breeches therefor, is provided with a spring-pressed ejector closure plate 18 provided with a leaf spring 20 urging the same into closed position relative to the ejector port 16.

Operable within the breech mechanism 10 is the customary bolt 22, the foregoing being of conventional and known design.

In certain types of guns, it is customary when loading the magazine thereof to force a series of cartridges, such as that indicated at 24, through the ejector opening 16 against the closure 18, and into the magazine of the gun, not shown, against the opposition of the magazine spring thereof. When it is desired to unload the magazine, it is heretofore necessary to depress or open the closure plate 18 by hand against the opposition of its spring, whereupon the magazine spring will feed or eject the cartridges 24 successively from the magazine through the opening 16. These two operations are heretofore somewhat awkward to perform, owing to the difficulty of adequately depressing the closure plate 18 against the opposition of the spring, through the relatively restricted ejector opening 16.

The attachment forming the subject matter of this invention therefore comprises means facilitating the opening of the closure plate 18 and further facilitating the discharge of cartridges therefrom or the insertion of cartridges therein.

For this purpose, the closure plate 18 having its leaf spring 20 is provided, as by means of welding or any other suitable manner, with a laterally extending boss or abutment 26 disposed in the rear portion of the ejector opening 16 and extending laterally therefrom, as shown in Figures 3 and 9. A retaining bracket comprising preferably a flexible metallic strip 28 of spring material is provided with an aperture 30 by means of which the same may be secured to the exterior surface of the breech casing 10 by means of the same fastening bolt 32 by which the spring 20 of the ejector closure plate 18 is fastened. The forward end of the resilient plate 28 is provided with a semi-cylindrical transverse groove or recess 34 facing toward the adjacent exterior surface of the casing member 10, which constitutes a hinge for pivotally receiving a closure-actuating plate 38.

As shown best in Figure 5, the closure-operating plate 38 is provided adjacent its rear edge 55 with a slot 40 which is received within the semi-cylindrical groove 34 to comprise therewith a hinge for mounting the plate 38. An elongated slot or opening 42 is provided in the plate in proper position to register with the ejector opening 16 when the plate is pressed against the surface

of the breech casing 10. Adjacent the opening 42 and between the same and the hinge slot 40, the plate 38 is provided with an inwardly extending lug 44 which is so positioned as to engage and abut the above mentioned lug 26 when the plate 38 is pivoted into its operative position. It will thus be seen that as so far described, the plate 38 may be moved to the position shown in Figure 9, whereupon when the lug 44 engages the lug 26 and the plate 38 is depressed inwardly against the casing 10, the closure plate 18 is forced open against the opposition of its spring 20, whereby a cartridge 24 may be inserted through the aligned and registering openings 42 and 16 into the magazine against the opposition of the spring therein, or whereby the spring of the magazine may successively eject the cartridges 24 therefrom.

To further facilitate the feed of cartridges into or from the magazine, when the attachment of this invention is manipulated, there is provided a guide means to assist the closure plate 18 to form a guide or baffle for directing the cartridges in their travel through the port 16. For this purpose, a spring member 46 is positioned within the breech mechanism casing 10 being retained at one end by a bolt or other fastening means 48, and being attached at its other extremity to an operating plunger 50 slidably disposed in an aperture or bore in the side of the casing 10. This spring, as shown in Figures 3 and 9, is disposed on the opposite side of the breech casing 10 from the ejector opening 16. The spring member 46 is so shaped and positioned that when the actuating plunger 50 is depressed inwardly of the casing 10, the spring is bent into a position in alignment with and in close proximity to the end of the ejector closure 18 when the latter is in its open position, as shown in Figure 9. When so positioned, the closure 18 and spring 46 comprise an aligned baffle or guide directing the cartridge 24 as the same is forced into or ejected from the magazine.

Secured by the bolt 48 to the exterior surface of the casing 10 is a leaf spring 52 whose outer extremity 54 bears against the outer surface of the casing 10, and which is intermediate its ends secured to the plunger 50, as by means of fastening nuts 56. This spring resiliently urges the plunger 50 outwardly of the casing, withdrawing the spring 46 into its retracted position, as shown in Figure 3, whereby the same together with the plunger 50 and bolt 48 are out of the path of travel of the bolt 22.

From the foregoing, the operation of the device will now be readily understood. When it is desired to insert cartridges into or remove the cartridges from a magazine, breech 10 is grasped by one hand of the user, a finger or fingers depressing the plunger 50 and urging the spring 46 in the position shown in Figure 9, and when the finger plate 38 is pressed into the position shown in Figure 9, by a finger of the same hand, cartridges 24 may be forced into the magazine against the opposition of the spring therein, or by merely opening the plate 18 and operating the button 58, the spring within the magazine will discharge the cartridges 24 successively from the port 16. Thus, it will be seen that the device may be manipulated by one hand of the user, and that the cartridges are adequately guided into and out of the magazine. Since the cartridges are ejected through the opening 42 of the plate which operates the

closure 18, it will be seen that there is no interference with the travel of the cartridges arising from the manipulation of the plate.

From the foregoing, the principle of operating the invention will be readily understood, and further explanation is believed to be unnecessary. However, since numerous modifications and equivalents will readily occur to those skilled in the art after a consideration of the foregoing specification and accompanying drawings, it is not intended to limit the invention to the exact construction shown and described.

Accordingly, all suitable modifications and equivalents may be resorted to falling within the scope of the appended claims.

Having thus described the invention, what is claimed as new is:

1. An attachment for the breech casing of magazine guns having an ejector port and a port closure therein, comprising a bracket attachable to the side of a breech casing, an operating plate pivoted to said bracket, and a lug on said plate insertable into the ejector port and engageable with the closure to open the closure when the plate is moved towards said casing.

2. The combination of claim 1 including an opening in said operating plate registerable with said ejector opening to provide passage of cartridges through said opening and port when said plate is moved to its closure opening position.

3. In combination with the breech casing of a magazine gun, an ejector port, an ejector port closure, a closure spring biasing said closure into closed position, a closure operating plate hinged to said breech casing, a closure operating lug on the outside of said plate, said lug being insertable through said port to engage and open said closure when said plate is moved to its operative position.

4. The combination of claim 3 including a closure lug on said closure extending into said port for engagement and actuation by said operating lug.

5. The combination of claim 3 wherein said plate is hinged to a bracket, said bracket being secured to the exterior surface of said breech casing.

6. The combination of claim 5 wherein said bracket and said closure spring are secured to said breech casing by a common fastening means.

7. The combination of claim 3 including a cartridge guide in said breech casing and operating means for positioning said guide in alignment with said closure plate in its opened position.

8. The combination of claim 7 wherein said guide comprises a flexible strip, said operating means comprising a plunger engageable with said strip to deform the same into its guiding position.

9. The combination of claim 8 including a leaf spring for returning said plunger to its inoperative position.

10. The combination of claim 9 wherein said leaf spring and said strip are secured to said breech casing by a common fastening means.

JOHN T. HANSEN.
